(57) **CLAIM**

The ornamental design for a retractable hook and hook retainer to be used in hand lamp, as shown and described.

DESCRIPTION

FIG. 1 is a perspective view of a retractable hook and hook retainer to be used in hand lamp showing my invention;
 FIG. 2 is a rear elevational view of the invention;
 FIG. 3 is a right-side elevational view of the invention;
 FIG. 4 is a left-side elevational view of the invention;
 FIG. 5 is a front elevational view of the invention;
 FIG. 6 is a top plan view of the invention;
 FIG. 7 is another front elevational view showing the extended hook, the two circular arrows included demonstrate that the hook is rotatable; and,
 FIG. 8 is another left-side elevational view showing the extended hook, the two circular arrows included demonstrate that the hook is rotatable.
 The broken line showing of hand lamp is included for the purpose of illustrating environment structure and forms no part of the claimed design.
